UNITED STATES PATENT OFFICE.

EDWARD J. ZAHNER, OF CANTON, OHIO.

SHEET-METAL HOUSE.

1,253,763.

Specification of Letters Patent. Patented Jan. 15, 1918.

Application filed June 22, 1917. Serial No. 176,434.

To all whom it may concern:

Be it known that I, EDWARD J. ZAHNER, a citizen of the United States, residing at Canton, in the county of Stark and State of Ohio, have invented a new and useful Sheet-Metal House, of which the following is a specification.

This invention relates to an improved construction of sheet metal houses and has 10 special reference to houses of this character which are designed to be quickly and readily assembled or torn down by unskilled workmen, the construction being such that no bolts or rivets or their equivalents are necessary in the assembling of the house.

The object of the present invention is to provide a sheet metal house of the character referred to which may be formed of sections and readily assembled and secured together 20 and which shall be strong, durable and tight against the wind and weather.

Another object is the provision of a sheet metal house of the character referred to in which no bolts or rivets or their equivalents 25 are used in securing the sheets in place, thus making the construction especially adaptable for temporary structures as the sheets are not marred or disfigured in any way and may be used for any other purpose after the 30 house is torn down.

A still further object is the provision of a sheet metal house comprised of spaced ribs between which metal sheets are received, the entire structure being clamped together by 35 means of cables, thus providing a building which may be easily and quickly assembled or torn down.

With these objects in view the invention consists in the novel construction and arrangement of parts, hereinafter described, 40 illustrated in the accompanying drawings, and particularly pointed out in the appended claims, it being understood that various changes in the form, proportions, 45 size and minor details of construction may be made within the scope of the appended claims, without departing from the spirit or sacrificing any of the advantages of the invention.

50 In the accompanying drawing:

Figure 1 is a side elevation of a house constructed in accordance with my invention.

Fig. 2 is an end elevation of the same.

Fig. 3 is a vertical transverse section 55 through the house.

Fig. 4 is a longitudinal section through a portion of the wall adjacent one corner thereof showing the cable for binding the structure together.

Fig. 5 is a detail elevation of a portion of the interior of the wall showing the cable and cable lock for clamping the same.

Fig. 6 is an interior elevation of a portion of the base and wedge and lug which holds 65 the lower end of each vertical rib in position.

Fig. 7 is a section on the line 7—7, Fig. 6.

Fig. 8 is an exterior view of a portion of 70 one of the horizontal ribs.

Fig. 9 is a section on the line 9—9, Fig. 8.

Fig. 10 is a horizontal section through a window frame or door casing.

Similar numerals of reference indicate 75 corresponding parts throughout the several figures of the drawings.

The invention comprises generally a base upon which are mounted vertical ribs between which sheet metal plates are located, said vertical ribs and plates being clamped 80 or bound together by means of a cable extending along the entire length or width of the building and connected to each rib by means of a cable lock, this cable being preferably located at the upper extremities of 85 the vertical ribs while the lower extremities thereof are connected to the base in the proper spaced relation by means of a lug and wedge. These vertical ribs are preferably curved toward the center of the building, a curved roof rib of similar construction to the vertical ribs bridging the space between each oppositely disposed pair of vertical ribs, plates being clamped between the roof ribs in the same manner in which 95 they are clamped between the vertical ribs and horizontal ribs being provided at the joint between the vertical plates and the roof plates. All of the ribs are provided with channels into which the edges of the 100 plates are received thus making a water tight joint. Window frames and door casings are inserted between the vertical ribs at desired intervals.

Referring more especially to the construction illustrated in the accompanying drawings the numeral 1 indicates the base which is anchored to the ground by suitable tie

rods 2, said base comprising the channel portion 3 having the up-turned horizontal flange 4 formed upon the upper side thereof, said flange being provided with the off-set portion 5. The vertical ribs 6 are curved slightly toward the longitudinal center of the building and are mounted upon the base in proper spaced relation with each other by means of lugs and wedges hereinafter described. Each vertical rib comprises the outer half-round portions 7 provided with a central strengthening corrugation or rib 8 and with similar ribs or corrugations 9 at each side. A central slot 10 is formed upon the interior side of each rib 6, rectangular reinforcing or strengthening ribs or projections being formed along the edges of said slot, the extremities of the sheet or plate from which the rib 6 is formed being turned outwardly forming flanges 11 which are spaced from or parallel to the interior walls 12 of the half-round portion of the rib, thus forming channels in which the edges of the sheets 13 are received.

25 A lug 14 is provided in the lower end of the half round portion of each vertical rib 6 and a wedge 15 is driven through a suitable aperture in the base 1 and co-acts with said lug to properly space the lower extremities of the vertical rib 6 upon the base and to secure the lower extremities of said ribs to the base.

30 A corner rib 16 is located at each corner of the building and as constructed is very similar to the vertical ribs 6 with the exception that the channels which receive the edges of the sheets are necessarily located at right angles to each other instead of in alignment as in the vertical ribs 6. Each 35 of these corner ribs is provided with a pair of brackets 17 located at right angles to each other, each bracket having an off-set portion 18 through which the screw threaded extremity 19 of a cable or rod is located, 40 a suitable washer 21 and nut 22 being provided upon the screw threaded extremity of each cable or rod 20. Located at the upper extremity of each of the vertical ribs and upon the interior thereof is a cable lock 23 45 which is formed from a flat plate of metal and provided with the oppositely disposed wings 24 which are arranged to be located within the half round portion of the vertical rib and against the walls 12, said plate extending through the slot 10 and provided 50 near its inner extremity with a locking plate 25 which is "spot" welded or otherwise connected to the plate 23, the attached extremity of said spring plate bearing against one of 55 the rectangular reinforcing ribs thus holding the cable lock in position. An aperture 26 is formed in the plate 23 and a similar aperture 27 is formed in the spring plate 25, these apertures being eccentric with 60 relation to each other and the cable or rod

20 is passed through said apertures after the sheet 13 has been properly set in place and the lower extremity of the rib 6 attached to the base as above described. The rib is then forced tightly against the adjacent edge of the plate 13 and the cable or rod pulled taut, the spring plate 25 thus forming a slight kink in the cable and retaining the rib in the proper vertical position clamping the plate tightly between said rib and the corner rib. The next adjacent plate 13 is then placed in position with reference to the vertical rib 6 which has thus been tightened and the next adjacent vertical rib 6 is placed in position and the cable 70 passed through the cable lock of said vertical rib and tightened therein, this operation being repeated as each vertical rib and vertical plate is placed in position.

75 At the upper edge of the vertical sheets 80 13 are located horizontally disposed ribs 28 each of these horizontal ribs comprising a rounded outer portion 29 having an upwardly disposed flat flange 30 at the upper edge thereof, an upwardly disposed straight 85 flange 31 being provided at the lower edge of said rounded portion and provided with an off-set portion 32 at the center thereof. At the upper extremity of the off-set portion 90 33 is provided an inwardly disposed angular flange 34, the edge of the plate or sheet being then bent downwardly and inwardly forming a spring flange 35 which is spaced from the flange 31 forming a channel to receive the upper edges of the sheets 13 while 95 the lower edges of the roof sheets 36 are received between the flanges 30 and 33.

100 The roof ribs 37 are curved as best shown in Fig. 3 of the drawings, said roof ribs being of the same construction as the vertical 105 ribs 6, and the roof sheets 36 are received into said roof ribs in the same manner as the sheets 13 are received into the ribs 6. The cable locks above described are preferably located at the points where the vertical and 110 roof ribs abut each other and if desired, especially in cases of extremely large buildings, a similar series of cable locks may be located through the longitudinal center of 115 the building and attached to the roof ribs.

120 Each of the end walls of the building is preferably straight and the vertical end ribs 38 are thus straight instead of curved as the ribs 6, the end sheets being also cut at their upper edges to conform to the curvature of the roof, this feature being best illustrated in Fig. 2 of the drawings. Suitable 125 door casings 39 and doors 40 are provided in the end walls as well as window frames 41 and sashes 42. These window frames and sashes are also provided at proper intervals along the side walls of the building. As the window and door constructions are both similar it is only thought necessary to describe the window and window frame con- 130

struction which is best illustrated in Fig. 10. The window frame is provided around its edges with a flat flange 43, the side flanges extending into channels formed in the adjacent vertical ribs while the upper and lower flanges 43 are received by upper and lower horizontally disposed ribs 44, which are of the same construction as the horizontal ribs 8. The window frame is provided with the inwardly disposed portion 45 having a channel 46 around its inner edge, said channel adapted to receive the flange 47 provided around the outer edge of the window sash 42 in order to form a weather tight joint.

15 I claim:

1. A sheet metal building composed of a plurality of ribs provided with oppositely disposed channels, sheets located between said ribs, the edges of said sheets being received in said channels, cable locks connected to said ribs and a cable passing through all of said cable locks and arranged to draw said ribs into tight engagement with the adjacent sheets.
- 25 2. A sheet metal building composed of spaced vertical ribs having oppositely disposed channels, sheets located between said ribs, the edges of said sheets received in said channels, means for drawing all of said ribs together to clamp the sheets therebetween, horizontal ribs provided with oppositely disposed channels located at the up-

per edges of said sheets, roof sheets carried between said horizontal ribs and roof ribs located between said roof sheets.

3. A sheet metal building composed of a rectangular base, spaced vertical ribs having oppositely disposed channels, means for detachably connecting said ribs to said base, sheets located between said ribs, the edges of said sheets received in said channels, means for drawing all of said ribs together to clamp the sheets therebetween, horizontal ribs, provided with oppositely disposed channels located at the upper edges of said sheets, roof sheets carried between said horizontal ribs and roof ribs located between said roof sheets.

4. A sheet metal building comprising a plurality of spaced curved rib sections having oppositely disposed channels therein, sheets located between said rib sections, the edges of said sheets received in said channels, cables connected to the rib section at one extremity of said building, cable locks provided upon the remaining rib sections, said cable arranged to pass through said cable locks to clamp all of said ribs and plates together and end walls connected to the rib sections at each end of said building.

In testimony that I claim the above I have hereunto subscribed my name.

EDWARD J. ZAHNER.
